CLAIM

The ornamental design for a packaging case, as shown and described.

DESCRIPTION

The file of this patent contains at least one drawing/photograph executed in color. Copies of this patent with color drawings/photographs will be provided by the Office upon request and payment of the necessary fee.

FIG. 1 is a perspective view of a packaging case, showing our new design;

FIG. 2 is a front view thereof;

FIG. 3 is a rear side view thereof;

FIG. 4 is a top plan view thereof;

FIG. 5 is a bottom plan view thereof; and,

FIG. 6 is a right side view thereof, the left side view being a mirror image of FIG. 6.

In the drawings, the broken lines are for the purpose of illustrating portions of the packaging case and forms no part of the claimed design. The dash-dotted lines denote the boundary of the claim and form no part of the claimed design. The blank areas surrounded by the dash-dotted lines form no part of the claimed design.
